UNITED STATES PATENT OFFICE.

EDMUND S. DICKEY, OF BALTIMORE COUNTY, MARYLAND, ASSIGNOR TO AMERICAN METER COMPANY, INC., OF NEW YORK, N. Y., A CORPORATION OF DELAWARE.

GAS-METER.

1,306,218.

Specification of Letters Patent. Patented June 10, 1919.

Application filed March 20, 1918. Serial No. 223,576.

To all whom it may concern:

Be it known that I, EDMUND S. DICKEY, a citizen of the United States, residing in the county of Baltimore and State of Maryland, 5 have invented certain new and useful Improvements in Gas-Meters, of which the following is a specification.

This invention relates to improvements in dry type gas meters, and more particularly 10 to valves for such meters.

Heretofore, as far as I am aware, valves for gas meters of the two valve type have been made in a single piece, and in order to get increased capacity in the meter, the 15 size of the valve has been increased, with the obvious purpose of securing the greatest possible valve area for the quick intake and discharge of gas, in order to pass additional quantities of gas in a given time. This tendency to increase the size of the valves for 20 the purpose indicated, has reached a point where further increase in size becomes practically prohibitive for various reasons in connection with the present form of valve 25 construction.

One of the objects, therefore, of this invention, is to provide four valves instead of two, but to so construct and arrange the valves that they will work as two valve 30 units, which is accomplished by forming the valves in separate or individual sections, yoked together, the two sections of each valve operating as one pair or as a single unit. By this arrangement, greatly increased valve area is obtained, permitting 35 quick intake and discharge of gas, and the consequent increase in the capacity of the meter. With the two double or yoked valves for each meter, instead of two single valves 40 for each meter, I can, by the employment of suitable channels, leading from the valve seats to the meter diaphragms and casing, adapt the valves for use with meters having two diaphragms, or to a meter with four 45 diaphragms without changing the valves and valve seats themselves.

In adapting the two yoked valves to a two-diaphragm meter, of the ordinary type, in which there is a central partition in the 50 meter casing, dividing it into two separate compartments, one yoked valve will be mounted on the valve table on one side of the meter partition, to serve one diaphragm and its compartment, and the other valve 55 mounted on the other side of the partition,

to serve the other diaphragm and its compartment, and in the case of meter construction in which there are four diaphragms, or two pairs, each pair in a separate compartment, each yoked valve will in that case, 60 serve a pair of diaphragms, and its compartment, thus doubling the valve area, with corresponding increase in the ability of the meter for the prompt intake and discharge of gas. 65

In the ordinary meter construction, where two single valves are used, the valves are set at 90° for reciprocal action in coördination with the two diaphragms that they control, and for the purpose of preventing dead 70 center. In my improvements, the yoked valves or two pairs of single valves are also set at 90° on the valve table for the same purpose, and reasons, but I am, by reason of the construction of the valves and valve 75 seats, enabled to control through a single valve arm, a valve of double the size of the present meter valve, and accordingly obtain double the valve area without increase in valve stroke, or increase in the length of 80 travel of the valve upon its seat.

Another object of the invention is to provide a valve having large valve area for the quick intake and discharge of gas, without great increase in the size of individual 85 valve castings, which is an important consideration in valve construction, particularly with large meter valves, in which there is a tendency of the valves to warp or otherwise become distorted causing leakage and consequent inaccuracy in measurement, as well as increased friction and therefore, increased 90 meter resistance in operation.

A still further object of the invention is to provide a novel means for guiding the 95 valves in their reciprocating or sliding movement, in which friction is reduced to a minimum, and to provide a construction in which the valve guiding means will be self-cleaning, to prevent the undesirable results of 100 deposits of gas condensates or heavy oils.

With the foregoing and other objects in view, all looking to the general improvement of valves of this character, my invention consists in the novel arrangement and 105 construction of parts hereinafter described.

In the drawings illustrating the invention,

Figure 1 is a top plan view of a dry type gas meter, with the top removed, and the 110

valve housing broken away, to show the valves and valve operating shaft and guides.

Fig. 2 is an enlarged cross section, of one of the valves, taken on line *a*—*b* of a valve 5 shown in Fig. 1.

Fig. 3 is a cross section on line *c*—*d* through one of the valve sections of one of the valves shown in Fig. 1.

Fig. 4 is a top plan view of a portion of 10 the valve table, showing the relative location of the valve seats, of one valve, and

Fig. 5 is a perspective view of one of the valves, with a portion of one of the guides in 15 juxtaposition thereto.

15 Referring to the drawings, the numeral 1 designates the meter casing, 2 the front, 3 the rear, and 4 the sides of the casing. The numeral 5 designates the intake and 6, the outlet, it being understood that the meter 20 casing is, or may be of ordinary construction.

The numeral 7 designates the valve housing, provided with reach 8, leading to the intake. The valve table 9 is the usual table 25 employed in dry type gas meters, of ordinary construction, and below the table are arranged outlet channels 10, and suitable diaphragm channels 11, but since the invention here does not reside in the arrangement 30 of the diaphragm and casing channels, which is more particularly the subject matter of certain companion applications, they need not be further described in detail, and are shown only to bring out more clearly the 35 valve construction which forms the subject matter of this application.

The numeral 12 designates a valve and 13 the valve seats for a valve; and since the two valves and the seats therefor are identical, a detail description of one will serve 40 as a description of both. The valve seats are separated, an arrangement peculiar to this invention, and are secured to the valve table, and are provided with diaphragm ports 14, outlet ports 15 and casing ports 16, formed 45 between the side rails 17, end pieces 18 and intermediate cross pieces 19, all having their upper surfaces in the same plane, for bearing and sealing purposes. The valve seats 50 are braced centrally by braces 20 and 21, cast integral with the seats, the braces 20 inclining from the bottom toward the top, while the braces 21 incline downwardly. These braces are below the bearing surfaces 55 of the valve seats, to do away with unnecessary friction between the valve and the seats.

The valve comprises two sections 22, identical in construction, which are yoked together by parallel yoke bars 23, having turned ends 24, fitting in sockets or recesses 25 in opposite sides of the dome portion 26 of the sections, in which sockets the inturned ends are soldered or otherwise firmly held. Each section is provided with front and rear 60 flanges 27, smoothly finished on the under-

side for accurate and close fit upon the valve seats.

The numeral 28 designates two guides of angular construction, which are soldered or otherwise fastened to the valve table, one on 70 each side of the valve seat. The horizontal upper portions of the guides overhang the upper faces of the guide brackets 29, one of which is integral with the outer side of each valve section, the arrangement serving to accurately guide the valve in its movement upon its valve seats. The guides 28, it will be observed, are below the level of the valve seats, so as not to interfere with the proper grinding of the valve seats. The outer edges 80 of that part of the guide brackets that underlies the guides are serrated, as indicated at 30, for reducing friction between these parts, and presents a formation which makes the valve guides self-cleaning. 85

In meters of ordinary construction, the valve wrist pin is usually located at the center of the valve, but in the present construction, I mount this wrist pin 31, upon a separate wrist wire 32, which is soldered or 90 otherwise fastened to the two yoke bars of the valve, as best shown in Figs. 1 and 5, thus making the wrist wires serve as a reinforcement between the front and rear yoke bars, the wrist wire being centrally located 95 between the valve sections and extending beyond the front of the valve, and at right angles to the yoke bars.

The numeral 33 indicates the valve arms, there being two in number, one connected 100 with the control pin of one of the valves, and the other connected with the control pin of the other valve, both arms being mounted upon the single crank 34 of the valve operating shaft 35, which shaft is given rotary 105 movement through suitable or usual diaphragm and flagstaff connections. By the described arrangement and construction shown, I am able to obtain double the single valve area or capacity, and still retain simplicity of construction, by reason of forming the valve in two sections yoked together to operate as a single valve, with a single valve wrist pin and single valve arm, or in other words, I operate two valves in a single 110 meter, with the capacity of four valves from a valve operating shaft, having a single crank and two valve operating arms, instead of two single valves, as heretofore, which 115 obviously eliminates the necessity of duplication of valve wrist pins and valve arms, and the employment of double or triple crank valve operating shafts to control 120 multi-valve movement.

Having thus fully described my invention, what I claim is:

1. In a gas meter, in combination, a slide valve for controlling the flow of gas into and out of the meter diaphragm and casing, formed of a plurality of independent sec- 130

tions yoked together for simultaneous movement.

2. In a gas meter in combination, a plurality of separated valve seats having ports therethrough for the passage of gas to and from the diaphragm and meter casing, a slide valve formed of a plurality of separate sections yoked together, a section for each valve seat.
- 10 3. In a gas meter, in combination, a slide valve for controlling the flow of gas to and from the diaphragms and meter casing, said valve comprising two separate sections yoked together for simultaneous movement.
- 15 4. In a gas meter, in combination, four valve seats arranged in pairs, two valves for controlling the flow of gas to and from the meter diaphragms and casing, said valves each being formed in two separate 20 sections, one section for each valve seat, the sections of each valve being yoked together for simultaneous movement.
- 25 5. In a gas meter, in combination, a valve operating shaft, two valves for controlling the flow of gas to and from the meter diaphragms and casing, each valve being formed in two sections, yoked together for simultaneous movement, and a valve arm 30 for each valve and connected with the operating shaft.
- 35 6. In a gas meter, in combination, a valve operating shaft having a single crank, two valves for controlling the flow of gas to and from the meter diaphragms and casing, said valves being formed in separate sections yoked together for simultaneous movement, and a connection between the crank of the operating shaft and each of the valves.
- 40 7. In a gas meter, in combination, a slide valve for controlling the flow of gas into and out of the diaphragm, and meter casing,

formed of a plurality of separate sections yoked together for simultaneous movement, a valve operating shaft, and connections between the valve and the operating shaft, 45 at a point intermediate of the valve sections.

8. In a gas meter, in combination, a slide valve for controlling the flow of gas to and from the meter diaphragm and casing, and 50 formed of two separate sections, yoke bars connecting the sections for simultaneous movement, a wrist wire secured to the yoke bars between the valve sections and having means for connection with a valve operat- 55 ing shaft.

9. In a gas meter, in combination, a suitable casing, having a valve table therein, a valve seat on said table, guide bars secured to the table adjacent opposite sides 60 of the valve seat, and provided with horizontal angle portions, a valve on said seat, provided with a portion underlying the angle portions of the guide bars, said underlying portion being provided with serrated outer edges for the purpose set forth. 65

10. In a gas meter, in combination, a valve seat, a valve table, guide bars located parallel to the sides of the seat and separated therefrom, and mounted on the valve table, and 70 formed with angle portions, a valve having a portion underlying the angle portions of the guides, the outer edges of the said underlying portion of the valve being serrated for the purpose set forth. 75

In testimony whereof I affix my signature in presence of two witnesses.
